UNITED STATES PATENT OFFICE.

CHARLES B. YOUNG, OF AURORA, ILLINOIS.

JOURNAL-BEARING.

No. 799,819.

Specification of Letters Patent.

Patented Sept. 19, 1905.

Application filed October 28, 1904. Serial No. 230,306.

To all whom it may concern:

Be it known that I, CHARLES B. YOUNG, a citizen of the United States, residing in Aurora, in the county of Kane and State of Illinois, have 5 invented a new and useful Improvement in Journal-Bearings, of which the following is a specification.

My invention relates to journal-bearings for car-axles.

- 10 Journal-bearings for car-axles as heretofore constructed have been made in various ways, either a brass back with a thin lead lining, a brass shell filled with babbitt, or a malleable-iron back in combination with brass and Bab-
15 bitt metal. In all these cases either the babbitt or brass formed the cylindrical surface to wear against the cylindrical surface of the axle, while the bearing-surface at the ends to wear against the shoulders or collars of the
20 axle has invariably been of brass. The end-thrust wear and friction is very considerable, especially on railroads having numerous curves, and the friction and wear of the hard-metal axle against the hard-metal ends of the
25 journal-bearings not only increases the draft of the train, but also materially diminishes the life and durability of the journal-bearings and journals of the axles. This wear due to end thrust shortens the life of a bearing con-
30 siderably, as a bearing worn at the ends must be removed and put into scrap.

The object of my invention is to provide a journal-bearing which, while practically inde-
35 structible in its main body, may have the worn parts removed in a very simple manner.

My invention consists in the means I em-
ploy to practically accomplish this object or
result—that is to say, it consists in the novel
40 construction of parts and devices and in the
novel combinations of parts and devices herein
shown and described.

In the accompanying drawings, forming a part of this specification, Figure 1 is a central longitudinal section of a journal-bearing embodying my invention. Fig. 2 is a bottom view of the journal-brass before the babbitt or soft metal is applied. Fig. 3 is a cross-section on line 3 3 of Fig. 1, showing the brass without the Babbitt metal. Fig. 4 is a longi-
50 tudinal section showing a modification in which the brass end segments are omitted.

In the drawings, A represents the brass, the same being preferably of steel or malleable iron. The steel or malleable iron or hard-
55 metal brass A is provided with a chamber or recess α to receive the babbitt or soft-metal wear-plate B, said chamber or recess having

side walls α' to confine the babbitt. The steel or malleable iron or hard-metal brass A is preferably provided with end segments D, of 60 brass, the same having integral dovetail tongues d , fitting in dovetail recesses α^2 of the brass to retain the brass segments in place. The end segments D are further provided with dovetail notches or recesses d' to receive the 65 babbitt and permanently secure the babbitt-bearing to the brass. The babbitt B also enters the dovetail notches α^2 in the brass A and fills the interstices between the walls of said notches or recesses and the lugs d on the brass 70 end pieces D. In the modification illustrated in Fig. 4, where the brass end segments D are omitted, the dovetail recesses α^2 in the brass A receive the babbitt and firmly secure the babbitt wear-plate in the brass. The babbitt 75 or soft-metal wear-plate B has an integral end flange or shoulder b , which embraces and covers the brass end piece D and forms an end-thrust bearing for the collar or shoulder f of the axle-journal F, and at the opposite end the 80 babbitt or soft-metal wear-plate B has a curved or rounded shoulder or integral flange b' , which embraces the other brass end segment D and forms an end-thrust babbitt wearing-
85 surface for the collar or shoulder f' of the axle. The cast-iron or hard-metal brass A is provided at each end with transverse seg-
90 mental shoulders or channels α^3 to receive the brass end segments D. Where the brass end segments D are omitted, as in Fig. 4, the in-
95 tegral end-thrust bearing shoulders or flanges of the babbitt or soft-metal wear-plate fills the transverse segmental channels α^3 .

I claim—

In a journal-bearing for car-axles, the com- 95 bination with the brass having at the ends thereof transverse segmental channels or shoulders to receive end bearing-pieces, sep-
arate inserted end bearing-pieces fitting in said channels of the brass, and a babbitt or 100 soft-metal wear-plate having integral end bearing flanges or shoulders embracing and covering said inserted end pieces, said brass having dovetail recesses and said separate inserted segmental end pieces having integral 105 tongues or lugs fitting in the recesses of the brass and said separate inserted end pieces having dovetail notches or recesses to receive the integral lugs of the babbitt or soft-metal wear-plate, substantially as specified.

C. B. YOUNG.
